UNITED STATES PATENT OFFICE

1,970,296

AIR CONDITIONER

Walter L. Fleisher, New York, N. Y.

Application August 19, 1932, Serial No. 629,483

3 Claims. (Cl. 257—9)

This invention relates to steam jet refrigeration systems and particularly to steam jet refrigerating systems which are adapted for use for air conditioning.

5 One object of the invention is to provide a simple and economical steam jet refrigeration system.

Another object of the invention is to provide an air conditioning apparatus which is well 10 adapted for both summer cooling and winter heating.

In steam jet refrigerating systems the water or other liquid being evaporated in a chamber in which the pressure is maintained below atmospheric pressure, it is necessary to provide a gravity head between the evaporation chamber and the inlet to the cooled liquid circulating pump. In the systems of the prior art this has 15 made necessary the use of a considerable length 20 of vertical piping between the evaporator and the pump.

In accordance with a specific preferred embodiment of my invention the evaporator chamber and cooling interchanger are constructed as 25 a unit, the evaporation chamber being located above and connected with the upper end of vertically arranged cooled liquid passages of the interchanger. The cooled liquid pump is mounted 30 below the interchanger and connected to the lower end of the interchanger passages which are made of sufficient length so as not only to provide sufficient surface for heat interchange but also to provide the proper gravity head for efficient 35 operation of the circulating pump.

40 This type of construction provides a compact refrigeration unit which is economical in construction, space requirements and operating cost. The integral construction of the evaporation chamber and interchanger reduces the number of pieces of apparatus required as it eliminates the necessity of a separate interchanger. The elimination of the usual header between the evaporation chamber and the pump eliminates 45 the possibility of loss due to the absorption of heat by the cooled liquid as it passes through that portion of the system.

Further, the system is particularly suited for use in air conditioning systems and when so used steam may be supplied to the combination 50 evaporation-interchanger unit for heating the air in the winter time.

These and other objects and features of my invention can be more readily understood by reference to the following detailed description 55 in connection with the drawing in which:

Fig. 1 is an elevation of one embodiment of the steam ejector refrigeration unit of my invention in an air conditioning system;

And Fig. 2 is a partial section taken along the dash-dot line 2—2 of Fig. 1.

60 Referring to the drawing, the refrigeration unit comprises an evaporation chamber 1 having a primary steam ejector 2 connected thereto. Steam is supplied to the primary ejector 2 from a supply pipe 4 through the nozzle 3. The outlet 65 of the primary ejector 2 is connected to the primary condenser 5 through which cooling water is circulated by means of the pipes 6. The primary condenser 5 is also provided with a secondary steam ejector 7 to which steam is supplied 70 through the branch pipe 8. The outlet of this secondary ejector 7 is connected to the secondary condenser 9 through which cooling water is circulated by means of the pipes 11. The secondary condenser 9 is provided with a tertiary 75 steam ejector 10. The condensate water from the primary condenser 5 and the secondary condenser 9 is pumped off through the pipes 12 by means of the condensate pump 13 to the pipe 14 through which it may be supplied to the boiler 80 (not shown).

Three rows of vertical pipes, or interchanger 85 passages 15, 16 and 17, have their upper ends connected to the bottom of the evaporation chamber 1. The pipes 15 and 16 are provided with the usual type of helical fins to permit more efficient heat interchange. The pipe 17 is provided with a helical trough-like fin as described and claimed in my copending application Serial No. 563,480, filed September 18, 1931, which not only 90 provides for efficient heat interchange but also is adapted for humidifying when the apparatus is used for winter heating as will be described in more detail below.

95 The lower ends of the pipes 15, 16 and 17 are connected to a return header 18 which is connected through a pipe 19 to the inlet of a chilled water circulating pump 20. The outlet of the pump 20 is connected through the pipe 21 to the spray-nozzles 22 in the evaporation chamber 1. 100 The interchanger pipes 15, 16 and 17 and the return header 18 provide storage space for the column of water necessary to produce the required cooling effect.

105 The pipes 15, 16 and 17 run vertically through an air-conduit 32 through which air to be conditioned may be circulated by means of a fan (not shown) preferably located with its inlet connected to the left hand portion of the conduit to cause an air circulation as indicated by the arrows. 110

In the operation of the apparatus for cooling, the steam ejector unit produces a vacuum in the evaporation chamber 1, cooling the water therein by evaporation. The pump 20 circulates the 5 cooled water through the interchanger pipes 15, 16 and 17, heat being absorbed from the air circulated in the conduit 32 by the water as it passes through the pipes 15, 16 and 17. From the pump 20 the water is resupplied to the evaporation 10 chamber through the spray-nozzles 22 to be re-cooled and recirculated.

The interchanger pipes 15, 16 and 17 are made of sufficient length to provide the necessary gravity head at the inlet of the pump 20 to permit it 15 to operate efficiently against the high vacuum in the evaporation chamber 1.

The apparatus may be used for winter heating as well as for summer cooling. For this purpose the steam to the steam ejector refrigerating unit 20 is cut off by means of the valve 23 and steam is supplied to the interchanger pipes 15, 16 and 17 through the valve 26, pipe 27 and the evaporation chamber 1. When so operated the connection to the chilled water circulating pump 20 is closed 25 by means of the valve 25 and the connection from the return header 18 through the pipe 29 to the condensate pump 13 is opened at the valve 28, the lead from the condensers to the condensate pump being closed at the valve 24.

30 When so operated the air may be humidified by water supplied to the helical troughs on the pipe 17 through the pipe 31. The unevaporated water being drained off through the pipe 32. The operation of this humidifier unit is described in detail

35 in my copending application referred to above. A thermostat 34 located in the return pipe 21 controls the solenoid operated valve 33 in the steam line 4 to regulate the flow of steam to the 40 ejectors and consequently the cooling effect produced in the evaporation chamber 1. By locating the thermostat in the return pipe 21 where it is responsive to the temperature of the water after it has passed through the interchanger passages 45 it is possible to regulate the refrigerating effect in response not only to the temperature of the cooled water but also to the amount of heat absorbed in the interchanger passages. In this way the 50 refrigeration effect is automatically regulated to take care of variations in the temperature and quantity of air passed through the conduit 32.

Additional automatic control may be provided for the winter heating and humidifying operation or for other purposes.

While only a single embodiment of my invention 60 has been shown and described herein, it will,

of course, be understood that it is capable of various modifications without departing from the spirit and scope of my invention as set forth in the appended claims.

What is claimed is:

1. An air conditioning apparatus comprising an air conduit, a fluid reservoir, fluid sprays therein, a plurality of vertical pipes mounted in said conduit, having their upper ends connected to the lower portion of said reservoir and adapted to provide an efficient heat interchange between the fluid therein and the air in said conduit, a pump having an inlet connected to the lower ends of said pipes and an outlet connected to the sprays in said reservoir, a steam ejector unit connected to said reservoir to provide a vacuum therein for cooling the liquid circulated through said pipes and said reservoir by said pump, and means for supplying steam to said reservoir at certain periods for heating the air passing through said conduit. 80 85 90 95

2. An air conditioning apparatus comprising an air conduit through which the air to be conditioned is circulated, a fluid reservoir, a plurality of heat interchanger pipes mounted vertically in said conduit having their upper ends directly connected to said fluid reservoir, means connected to the lower end of said pipes for circulating fluid through said reservoir and said pipes, means for maintaining a reduced pressure in said reservoir for cooling the fluid circulated therethrough, and means for supplying a heating fluid to said reservoir and said pipes at certain periods for heating. 100 105 110

3. An air conditioning apparatus comprising an air conduit adapted to carry the air to be conditioned, a fluid reservoir, a plurality of pipes arranged vertically in said conduit, having their upper ends directly connected to said reservoir and each provided with a helical fin to facilitate 115 the interchange of heat between the air in said conduit and the fluid in the pipes, the fin for at least one of said pipes being in the form of a trough, a pump having an inlet connected to the lower end of said pipes and an outlet connected to said fluid reservoir for circulating fluid through said pipes and reservoir, means for maintaining a reduced pressure in said reservoir for cooling the circulated fluid, means for supplying steam to said reservoir and pipes at certain periods 120 125 130 for heating the air in said conduit, and means for supplying water to the trough-like fin during the heating operation. 135
